BALL ROLLING GAME

Bon G. MacDougall, Chicago, Ill., assignor to Raymond T. Moloney, Chicago, Ill.

Application November 21, 1938, Serial No. 241,555

2 Claims. (Cl. 273—41)

The invention relates to a ball rolling game of the pin ball type modified in a novel manner to simulate a bowling game.

Games of this sort, utilizing bowling pins have heretofore been used with the ten bowling pins hinged to the ball rolling surface. In the present game it is proposed to hinge the bowling pins intermediate their ends in a statically balanced manner on horizontal axes disposed above the ball rolling surface. Each pin is disposed in an electric circuit and carries a contact switch arm cooperable with overhead contact wires, also in the circuit, so that when a pin is impinged by a rolling ball, it will swing about its axis and cause the associated switch arm to contact the said overhead wire, thereby momentarily closing the circuit to energize a relay which may in turn operate an auxiliary, such for example, as a score register device.

The main object of the invention is to provide an improved amusement game of the ball rolling type.

Another object is to provide a game of the pin ball type, simulating a bowling game in a novel manner.

Still another object is to provide a novel way of supporting miniature or simulated bowling pins in relation to a ball rolling surface.

Another important object is to utilize the bowling pins in a manner when hit by a ball to cooperate with improved circuit means to cause operation of an electrical auxiliary such as a score register.

Another general object is to provide a novel suspended type of obstacle for ball rolling games in which the obstacle, or obstacles are hingedly carried on an axis above the table, said obstacles having generally the shape of a bowling pin or some equivalent, analogous shape.

Other important objects will become apparent as the disclosure is more fully made.

In the drawings, illustrating one form which the invention may assume in practice:

Figure 1 is a general plan view of the improved game, there being included, a typical wiring diagram for an electric circuit;

Figure 2 is an enlarged, fragmentary, cross sectional view, taken on the line 2—2 of Figure 1, looking in the direction of the arrows;

Figure 3 is a cross sectional view taken along the line 3—3 of Figure 1, looking in the indicated direction; and,

Figure 4 is a detail, cross sectional view through a bowling pin obstacle, taken along the line 4—4 of Figure 3, as indicated.

By way of example, the game may be housed in a conventional pin ball game type of cabinet 10, having a front wall 11 and a ball rolling table 12 sloped slightly from the horizontal with its low end disposed adjacent the front wall 11. The forward or low end of the table carries a ball deflector plate 13 to lead spent balls to a ball drop opening 14 in a manner well understood in this art. The upper or high end of the table 10 carries the usual arch plate 15 and ball rebound bumper spring 16. Along the right hand side of the table, as viewed in Figure 1, is a longitudinal partition 17 formed as a continuation of the plate 13, thereby providing a ball projection passage 18 along which balls may be projected by a manually operable spring plunger projector 19 of a kind known in the art. A ball so projected goes along the passage 18, around the arch 15 and hits the bumper 16, to rebound and then by gravity roll down the table to the low end thereof and finally to be received by the ball drop opening 14. By conventional means, not shown, these dropped balls are returnable one at a time to a position in the passage 18 to be acted upon by the projector 19. At the left hand side of the game is another partition 20, which in height is the counterpart of the one 17. A top glass panel 21 serves to cover the game.

These side partition members 17 and 20 serve as supports for a series of four spaced transverse rods or shafts 22 made of conductor material, said rods being at their ends respectively secured in upright brackets 23. The supports 17 and 20 are of wood, in other words, of non-conductor material.

As appears in Figure 1 these shafts 22 are cross connected by a wire 24, leading to one side of a source of electrical energy, represented by a plug 25. A lead 26 then goes to an electromagnetic device 27, having an armature core 28 connected through a link 29 to the actuator member 30 for a counting or registering device, generally depicted at 31. This latter device may be mounted in any convenient place on or about the cabinet 10. From the coil 27 is led a wire 32 connected to a cross wire 33 mounted between suitable posts 34 as shown, at the low end of the table 12. Similar posts 35 are mounted on opposite sides at the high end of the table and they serve to carry a cross wire 36. These two overhead cross wires 33 and 36 are inter-connected by a series of four, spaced, lengthwise running, overhead wires 37.

Pivotaly carried intermediate their ends on the shafts 22, are a series of ten obstacle members

which may be in the form of bowling pins 38, each having a bearing bushing 39 for mounting the same in the usual bowling set-up arrangement on said shafts 22. Means 40 is provided to hold each pin in its selected position against axial displacement along its shaft mounting. Each obstacle pin at its lower end is loaded with a weight counterbalance 41 and is provided with a rubber bumper ring 42 to receive the impact of a steel ball rolling down the table, such a ball being illustrated at 43. These obstacle pins 38 are respectively positioned for rotation or swinging movement adjacent a wire 37 so that a crank arm 44 associated with each pin 38 may when the pin swings engage a wire 37, each arm 44 being provided with a lateral extension 45 for that purpose. It is also to be noted that each arm 44 has metallic contact with the corresponding sleeve 39 and shaft 22. This completes the detail description of the parts of the improved game.

In operation, the respective obstacle pins 38 by means of the weights 41 and crank arms 44 are counterbalanced normally to hold the pins in a vertical position as shown in Figure 2. When a steel or other heavy ball is now projected by the element 19 it eventually gravitates down the inclined table 12 in the manner heretofore described. Should the ball roll against one or more pins 38 in its course and impinge against same, it follows that such contacted pins will be swung around their axes and have enough energy imparted to same to cause the associated arms 44 and their extensions 45 to contact, one or more times with the overhead wire 37 associated therewith. Thus, the circuit described is repeatedly closed to energize the device 27 and operate the register 31 to count the number of contacts made for scoring purposes. Any suitable number of balls may be used as desired. When a ball having bumped and operated a pin is clear of the pin, the pin balancing means, of course, is instantly operative to restore the pin to its normal,

vertical position. While the obstacle herein shown is specifically shaped to simulate a bowling pin, it is obviously possible to utilize some other shape just as well, the important thing being that whatever its shape, the pin be pivotally carried above and clear of the table.

It can now be seen that an improved and simple game structure has been provided to achieve the objects of the invention as heretofore recited.

It is the intention to cover herein all changes and modifications of the example disclosed, which do not in material respects constitute departures from the spirit and scope of the invention, as hereinafter claimed.

What is claimed is:

1. In a ball rolling game, a substantially horizontal table over which a ball is rollable, parallel spaced stationary cross shafts including means to support same over the table, parallel spaced overhead wires including means to support same over the table at right angles to the shafts, pins hinged respectively on the shafts, said shafts and wires comprising a normally open electrical circuit, and each pin having a contact member to hit an associated wire when a ball rolling on the table engages and swings a pin to close the said electric circuit.

2. In a ball rolling game, a substantially horizontal table over which a ball is rollable, parallel spaced stationary cross shafts including means to support same over the table, parallel spaced overhead wires including means to support same over the table at right angles to the shafts, pins hinged respectively on the shafts, said shafts and wires comprising a normally open electrical circuit and each pin having a contact member to hit an associated wire when a ball rolling on the table engages and swings a pin, the contact members being irregularly shaped and each including an extension and connected to its pin intermediate the ends of the latter.

BON G. MACDOUGALL.
